POCKET KNIFE HANDLE

William W. Lillard, Beaumont, Calif.

Application October 9, 1950, Serial No. 189,180

4 Claims. (Cl. 30—125)

1

The present invention relates generally to knives such as are commonly carried on the person of the user, and it relates more specifically to means for compactly disposing in such knives devices for sharpening blades and other elements of the knives.

Often it is desirable or essential to the user that the blade of his knife have a keen cutting edge. This ordinarily calls for sharpening the blade just before and during its use, if the use is prolonged. The smallest knife blade sharpening stones in common use are bulkier than many pocket knives. There have been proposed blade sharpening devices permanently attached to some element of a knife. Such devices considerably increased the bulk of the knife and its manufacturing cost. Also, there have been proposed stiff abrasive stones of well known kinds to be inserted in grooves provided in outer handle elements of the knives. Such stones if thin enough to not be objectionably bulky were very likely to be fractured during an ordinary use of the knives. They were objectionable also because of having a more or less grimy and unclean surface which often would soil a user's hands or clothing.

It is one object of the present invention to provide for conveniently sharpening the blades of a knife means which include a sheath-like element of the knife and an abrasive element readily inserted in said sheath element and self-fastened therein for easy withdrawal. It is another object of my invention to provide in a pocket knife handle, an inexpensively constructed sheath-like element which does not increase the bulk of the handle appreciably.

It is another object of my invention to provide a sheath-like receptacle in a knife handle under a transparent molding strip portion thereof so constructed that an indicia-bearing card may be readily inserted in said sheath element and permanently secured therein after the knife handle has left the factory.

A feature of my invention resides in the provision of means for securing coaction of a flexible, resilient, blade-sharpening member having projecting abrasive teeth-like elements and a pocket knife having therein a sheath receptacle for receiving said member so that the teeth-like elements are pressed lightly against a wall element of the receptacle and cause a retaining action on the sharpening member.

Other objects and advantageous features of my invention will appear as the description proceeds.

2

The present application is a continuation-in-part of my application for patent Ser. No. 715,078, filed December 9, 1946, which application has been abandoned since the filing date of the present application.

Referring to the drawings which form a part of the specification:

Figure 1 is a side elevational view of a pocket knife in which certain features of my improvement are embodied, certain indicia carried on an interiorly disposed element of the knife being shown in full lines since the indicia are clearly visible. Figure 2 is a cross-sectional view of the structure of Figure 1 along the line 2—2 in the direction of the arrows, certain parts being omitted or broken away in part for sake of clarity. Figure 3 is an enlarged partial side view of a name-bearing card member effective to be self-attached in a sheath element of a knife structure such as that of Figure 1 after being inserted therein. Figure 4 is an enlarged, partial side view of a metal side plate element of a pocket knife which may be employed in carrying out a feature of my invention related to the structure of Figure 3. Figure 5 is a cross-section along the line 5—5 of Figure 4 and shows in phantom view a cooperative card element. Figure 6 is a side view, broken away in part, of Figure 3. Figure 7 is an enlarged side view, broken away in part, which shows a name-bearing card member that may be used in certain cases advantageously to replace a similar card member shown in Figure 3. Figure 8 is an enlarged, partial side edge view of a blade sharpening abrasive device self attachable in a sheath in the knife structure of Figure 2. Figure 9 is an enlarged, partial plan view of the structure of Figure 8. Figure 10 is an enlarged cross-sectional view of a blade sharpening device which may advantageously replace the device of Figure 8 in some cases.

In Figures 1 and 2, certain of my improvements are shown embodied in a pocket knife generally designated as 10 which, except as is hereinafter pointed out, may be of well known construction. The knife 10 may include two usual soft metal side plates 11 and 12 and an intermediate plate 13 of soft metal such as brass. Between the side plates may be pivotally mounted two knife blades 14 and 15 of well known construction on a steel pin member 16 which extends through the plates 11, 12 and 13 at a point adjacent one end of the knife. The ends of the pin 16 terminate in metallic bolster members 17 and 18 strongly secured as by brazing to the adjacent

ends (right ends as viewed in Figure 2) of the side plates 11 and 12. The bolster members are further described hereinafter. To the other (left) ends of the side plates 11 and 12 are secured bolster members 20 and 21, respectively, which will be further described hereinafter. A metallic pin 22 may extend through the plates 11, 12 and 13 and terminate in the bolster members 20 and 21.

Extending along the sides of the knife 10 between the bolster members 17 and 20 and between the bolster members 18 and 21 are molding strips 25 and 26, respectively. These strips may be made of suitable moldable material such as cellulose plastic materials known to the trade as Pyralin or Celluloid. The upper (as viewed in Figure 2) strip 25 may be of a suitable transparent material throughout or have a centrally disposed transparent section 25W arranged to serve as a window in a way and for a purpose to appear hereinafter, and the remainder of the strip may be opaque, if desired. In some cases the transparent window element 25W may be advantageously made of different material from the remainder of the strip. The strip 26 may be opaque throughout.

In the inwardly disposed face portion of the strip 25 is made a shallow lengthwise groove 27, preferably centrally disposed in the strip. When the strip 25 is in place next to the side plate 11 there is formed a sheath or pocket-like receptacle 28 for a purpose presently to appear. In the molding strip 26 may be made a shallow groove similar to the groove 27 to form with the side plate 12 a sheath 30 which may be larger than the sheath 28 to advantage in some knives.

To provide an easily used mouth or inlet 31 for the sheath 28, the bolster 17 may be made with a chamfered, recessed portion 32 beginning at a point a short distance inwardly from the outer end of the bolster and declining toward the side plate 11 at a point approximately even with the adjacent end of the molding strip 25. The left hand end (as viewed in Figure 2) of the sheath 28 is preferably closed by abutting against a square inner end of the bolster 20 which may be of usual construction. The bolster members 18 and 21 may be made with chamfered or beveled portions 35 and 36, respectively, which decline toward the side plate 12 at the ends of the strip 26 and form recessed inlets at each end thereof. The chamfered bolster portions 35 and 36 may be of substantially the same shape as that of the bolster portion 32 and be appropriately arranged as illustrated in Figure 2 to form a recessed inlet element for each end of the sheath 30. The ends of the pin 18 may be slightly enlarged and finished flush with the inclined surfaces of the bolster portions 17 and 18. The adjacent end of the pin 22 is finished flush with the inclined bolster portion 36.

The molding strips 25 and 26 may be held tightly against the side plates 11 and 12 by rivets 40 and 41 which pass through the strips on each side of the lengthwise groove in each strip and terminate in the side plates in a well known way. In addition to the rivets 40 and 41, the molding strips 25 and 26 are further fastened by a usual blade-spring pin 42 at one side of the sheaths. It will be understood as the description proceeds that for the purposes of the present invention the molding strips 25 and 26 may be fastened to the side plates 11 and 12, respectively, by any suitable devices which do not interfere with or limit the dimensions of the sheaths in the strips.

unnecessarily when the sheaths are used in ways soon to appear.

In carrying out one feature of my invention, I provide a composite card member generally designated as 50 which may be made up of a bottom sheet 51, a second sheet 52 and a top sheet 53. The sheet 52 may be of any desired color and will preferably have written on its upper surface by the purchaser his signature and home address and if desired may also bear the name of the merchant who sells the knife. The sheet 53 is made of some transparent resilient material such as cellulose of the brands known to the trade as Pyralin or Celluloid. The bottom sheet 51 may be made of some material such as fine grained emery cloth of well known construction which may have a roughened lower surface because of the granular particles 51t held on its lower face. It will be understood by those skilled in the use of emery cloth that the granular, teeth-like particles 51t are spaced closer together than is indicated in Figure 6. One or all of the sheets 51, 52 and 53 may be slightly resilient and have an arcuate form so that when the three sheets are cemented together in a well known way, the composite card 50 will normally (before assembled) have a slightly arcuate form as indicated in Figure 6 by the dot-and-dash outline of the card.

30 The card 50 has a cross-section for fitting snugly in the sheath 28 but is preferably slightly shorter than the length of the sheath so that when its leading (left) end is inserted in the sheath through the inlet 31 and pushed up against the bolster 20, the opposite end is disposed inwardly a short distance from the inlet 31. The card 50 may be pushed in the sheath past the inlet by any suitable device such as a flexible piece of paper card (not shown). The card 50 is held against the bolster 20 against displacement by severe jarring, for example, because of the digging or scratching engagement of the teeth-like particles 51t with the soft metal of the side plate 11. This engagement is made effective by the resilience of the straightened card 50 which tends to resume its arcuate form. Also, if desired, the right hand (as viewed in Figure 2) end of the sheet 53 may be easily cemented to the molding strip 25 and the resilience of the card 50 will be effective to press the sheet 53 against the molding strip and help secure a good cementing result. The cement (not shown) is preferably applied to the right hand end of the sheet 53 just before the card 50 is assembled in the sheath 28.

55 In some cases, it may be desirable to employ a name-bearing card 50' such as is illustrated in Figure 7 wherein the sheets 52 and 53 are made and assembled as explained in connection with the structure of Figure 6. These sheets are then cemented over a sheet 51' which may be approximately the same as the sheet 51 except that the sheet 51' has no roughened surface or granular teeth elements. Or the sheet 51' may 60 be omitted and the sheet 52 be made extra thick and of suitable tough, strong material. Where a name-bearing card is made according to the showing of Figure 7 and the disclosure of the present paragraph is employed, a side plate 11' such as is shown in Figure 5 may be provided and be of suitable metal and have minute teeth-like elements 11t unless the card 50' is to be cemented to the molding strip 25 as explained hereinbefore in connection with the card 50. 65 The teeth-like elements 11t' are effective to dig

into or bite the card 50' and hold it against displacement from the sheath 28 since the straightened card is pressed against the teeth 11t' because of its initial arcuate form and resilience.

To accomplish that important object of my invention which is to provide for blade sharpening purposes practicable, inexpensive means compactly assembled in a pocket knife to be easily removed to make possible a sharp cutting edge for the blades of the knife at any place or time the knife is to be used, an abrasive, flexible strip member 55 may have a width and thickness for fitting loosely in the sheath 30. As indicated in Figure 2, the length of the strip 55 is preferably such that it extends out a short distance beyond each end of the sheath 30 but does not extend beyond or above the recess at each end of the sheath. The recessed bolster construction at each end of the knife is advantageous since it permits the assembling of a sharpening strip 55 in the knife which is considerably longer than would be possible if the strip extended out of the sheath only at one end. Also, the strip may be inserted or withdrawn from either end of the knife. While in the knife properly, neither end portion of the strip 55 affects i. e. increases the bulk of the knife. Also, the abrasive strip serves to brace and strengthen the thin portion of the molding strip 26 adjacent the sheath 30.

The abrasive, blade sharpening strip 55 may be of any suitable construction so as to be flexible and to have on at least one side slightly projecting abrasive elements 55t which are effective to serve for blade sharpening purposes and for retaining the strip in the sheath 30 by action of the elements 55t digging into or clawing the soft metal of the side plate 12. Such a retaining action while positive permits a light pull on the strip 55 by a finger of the user in a finger slot 56 to easily remove the strip from the sheath 30. A strip of fine grained emery cloth (not shown) of well known construction will give reasonably good service in some cases. A sharpening strip 60 which includes strip members 61 and 62 of soft metal such as brass or bronze may have hammered into one or both side faces small particles of an abrasive material such as diamond dust or a hard refractory substance. Such a strip has some advantages which will be pointed further hereinafter in connection with a more specific description of the structure of Figure 10.

To make use of a sharpening strip constructed according to my invention, the strip is drawn from the sheath and is simply held against a firm flat object by the user's fingers of one hand, one finger at each end of the strip. With the other hand the knife blade is moved over the strip being pressed thereagainst in a well known way as is ordinarily done with widely used small abrasive sharpening stones. In some cases it may be preferable to fasten each end of the strip to a small flat object by rubber bands or strings (not shown).

In many cases, it will be satisfactory to have the sharpening strip 55 made as is set forth in U. S. Patent No. 2,105,915. Sharpening devices made according to the disclosure of the above mentioned patent are known to the trade as Flexstones or Plastones. In this product called Flexstone, the sizes of the abrasive particles throughout a strip are approximately uniform in size. That is, the partly protruding particles

on one side of a sharpening stone of Flexstone material or construction are of the same coarseness or fineness as those on the other side.

In most cases, it will be satisfactory and preferable to have abrasive, protruding particles 55t at least appreciably coarser than the abrasive particles 55t' on the other side of the strip. This construction is advantageous since it will permit a user who ordinarily will have only one blade sharpening strip 55 sheathed in his knife handle to employ the coarse grained side of the strip for relatively fast sharpening of a dull blade and to employ the finer grained side for finishing the sharpening process and giving the blade a smoother cutting edge than would be practicable with the coarser grained side.

The provision of the recessed, upwardly inclined bolster portions at each end of the sheath 30 necessarily flexes sections of the strip 55 20 while in the sheath and urges some of the teeth-like particles of the strip into strip-retaining engagement with the soft metal side plate 12. This retaining action may be increased by constructing the strip 55 to be slightly resilient and 25 to have normally (when out of the sheath) a slightly arcuate form as is indicated in Figure 8. Then when the strip is inserted in the sheath, the strip is mostly straightened into a flat form and the inherent resilience of the strip will increase 30 the pressure of the projecting abrasive particles against the side plate 12 and thus secure a self-fastening effect which is very advantageous.

It has been found in practice that a sharpening strip with relatively fine grain abrasive particles embedded in both sides of the strip and having a small amount of resilience is retained in a sheath 30 in a pocket knife handle against displacement by forcible jarring endwise of the 35 handle. Such a self-retaining action is obtained also where there is no inclined bolster inlet portion at the mouth or inlet proper of the sheath if the sharpening strip is resilient, flexible and slightly arcuate normally. Such a strip can be 40 used advantageously where in a pocket knife embodying my invention there are metallic bolster parts at one end only of the knife, or which omits the bolster parts altogether.

In Figure 10 is illustrated a composite sharpening strip 60 which may include two soft metal, thin strips 61, 62 fastened together by rivets (not shown) in a well known way to the opposite sides of a thin strip 63 having considerable resilience such as spring steel. Soft metal such as 50 brass or tin used in the thin strips 61 and 62 is quite flexible and if the steel strip 63 is slightly arcuate normally, the whole composite strip 60 normally will have the arcuate form approximately as is illustrated by the dot-and-dash outline in Figure 10. Such an arcuate form is 55 usually desirable for the reasons stated hereinbefore in connection with the strip of Figure 8. Into the exposed face of the strip 61 may be hammered, i. e. embedded in a well known way particles 61c of diamond dust or other hard abrasive material. Into the exposed face of the strip 62 may be hammered, i. e. embedded in a well known way, particles 61f of hard abrasive material which may be finer, i. e. smaller in size 60 than the particles 61c for the reasons explained hereinbefore in connection with sharpening a dull knife blade first on the side of an abrasive strip sharpening strip having somewhat coarser abrasive elements than are carried on the other side of the strip. The strip 60 being an all metal

strip is able to withstand things such as heat better than the strip 50.

It can be readily seen that several minor changes in the shape and dimensions of certain of the parts illustrated in the drawings may be made without involving invention. For example, the recessed element of the bolster 17 may be chamfered from the end of the molding strip out only to a point half way to the pin 16.

Having described my invention, I claim:

1. In a pocket knife, a handle including two metal side plates, a metallic bolster member secured to each end of said plates on the outwardly disposed face thereof, a molding strip permanently fastened to the outer face of each of said side plates between the bolster members thereon, a cavity formed in each of said molding strips lengthwise thereof and positioned inwardly from the outer surface of the associated molding strip, an inlet for each of said cavities adjacent an end of the associated molding strip, said inlets each including a recess formed in the adjacent bolster to have an inwardly disposed surface inclined inwardly toward the adjacent end of the associated cavity.

2. A pocket knife or the like including, a handle having two metal lateral side plates, bolster elements providing blade pivot bearings covering the ends of the outer sides of said lateral side plates, at least one of said bolster elements being chamfered to provide an inclined surface tapering to the inner end thereof thereby providing a substantially continuous surface with the outer surface of the lateral side plate which it engages, a molding strip extending between said chamfered bolster element and the bolster element at the other end of said lateral side plate, said molding element having a longitudinal recess in its inner face cooperating with the outer face of the adjoining lateral side plate to form a cavity thereby providing a sheath like structure having an opening adjacent to the inclined chamfered surface of the bolster element for the reception of indicia bearing cards, abrasive knife blade sharpening strips or the like, and means for securing said molding strip to the lateral side plate in areas which contact the plate.

3. A pocket knife or the like including, a handle having two metal lateral side plates, bolster elements providing blade pivot bearings covering

the ends of the outer sides of said lateral plates, with a plurality of said bolster elements, at least one on each side being chamfered to provide inclined surfaces tapering to the inner ends of the bolster elements thereby providing substantially continuous surfaces with the outer surfaces of the lateral side plates which they engage, molding strips extending between said bolster end elements on each of said lateral side plates, said molding strips each having a longitudinal recess in its inner face cooperating with the outer face of the lateral side plate which it engages to form a cavity thereby providing a sheathlike structure having an opening adjacent to the inclined chamfered surface of the bolster element, said molding strips being of transparent material enabling indicia bearing cards, abrasive strips or the like to be seen therethrough, and means for securing said molding strips to the lateral side plates in areas which contact the plates.

4. A pocket knife or the like including, a handle having two metal lateral side plates, bolster elements having chamfered inner ends, a molding strip extending over each of said side plates between the bolsters, each of said molding strips having a longitudinal recess in its inner face cooperating with the outer face of the lateral side plate to form a cavity thereby providing a sheath like structure having an endwise entrance opening therein for the reception of indicia bearing cards, abrasive knife blade sharpening strips or the like, and means for securing said molding strips to the lateral side plates in areas which contact the plates between the chamfered portions of the bolster elements.
